UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed December 20, 1924. Serial No. 757,130.

This invention relates to sound-deadening cabinets for typewriting machines, and one of its features is the provision of means whereby a completely enclosed typewriter 5 carriage may be manipulated by the insertion of the hand through a self-closing opening.

Sound-proof cabinets have been provided for typewriting machines in which special 10 carriage-control levers extend to the outside of the casing through slot-sealing cushions, and also sound-proof cabinets in which an opening adjacent the path of said levers and in front thereof is provided in order 15 that the hand may reach the carriage-controlling levers.

An object of the present invention is to provide a sound-deadening casing which, while simply designed for economical manu- 20 facture, is at the same time highly efficient in its noise-eliminating qualities.

One of its features is that the typewriter may be installed within the casing with lit- 25 tle or no alteration thereof.

Another feature is that the typewriter is completely enclosed within the casing ex- 30 cept for the keyboard-extension which pro- trudes through an opening in the casing.

The casing consists in one form of a 35 lower member and a hood or cover pivotally mounted on said lower member. The key- board of the machine extends to the exterior of the casing in order to render the type- keys operable, and the typewriter is other- 40 wise completely enclosed. Adjacent the carriage-control levers there is provided an opening formed between the cover and the casing which extends substantially the full width of the casing. Said opening is pro- 45 vided with a self-closing mechanism, which may consist of a double door and linkage arrangement, manually operable by means of finger-pieces at the ends, so that the doors may be swung open to reach the car- 50 rriage-controlling levers. The typing in the typewriter and the levers on the carriage may be seen through a transparent window at the top of the cover and in the path of the line of vision of the operative.

There is shown in the drawings a modifi- 55 cation of the closure in which different means for synchronizing the movement of the two doors is provided, and which consists of two geared sectors operatively con- nected and fast to the fulcrum shaft upon

which the doors swing, and one of the sectors is provided with a finger-piece for operating the same.

Another modification of the closure con- 60 sists of two flaps or flexible material having one of the edges fastened to the edges of 65 the opening and abutting against each other to effectively close the opening. In one case the flaps are made of celluloid covered with some sound-deadening material, while in 70 the other case the flaps are made of a layer of felt having a rubber backing. The finger is thrust through the opening to reach the levers, thereby separating the flaps, and the finger may be slid along the opening. 70

Another modification is illustrated, in 75 which the opening is provided with a clo- sure consisting of a single door rockably mounted at one edge and operable by means of pressure exerted thereon against a clos- 80 ing spring or by means of finger-pieces fast on the rock-shaft upon which the door is mounted.

Other features and advantages will here- 85 inafter appear.

In the accompanying drawings,

Figure 1 is a front view in elevation, showing the invention in its preferred form.

Figure 2 is a cross-sectional view in ele- 85 vation through the line 2—2 of Figure 1, showing the closure in its effective position.

Figure 3 is a cross-sectional view in eleva- 90 tion, showing the closure in its ineffective position and a finger manipulating the line-space lever of the typewriter.

Figure 4 is a modified form shown in cross-section, and illustrating other means for operating the closure.

Figure 5 is a front view in elevation, showing the mechanism illustrated in Fig- 95 ure 4.

Figure 6 illustrates another manner of closing the opening through which the car- riere-control levers are operated.

Figures 7 and 8 are respectively a front 100 view and a cross-sectional view of a closure comprising a single door and means for operating the same.

Figure 9 is a modified form of the closure shown in Figure 6, and shows the cover in 105 its open position in dot-and-dash lines.

This invention is illustrated as applied to an Underwood standard typewriting ma- 110 chine. Said machine comprises a frame and a carriage 11 disposed for letter-feed

travel. Upon said carriage there are mounted the shiftable platen-frames in which a platen 12 is journaled. For controlling the movements of the carriage and to line-space 5 a work-sheet around the platen, there are provided a line-space lever 13 and a carriage-release lever 14.

Typewriting machines of this general character are comparatively noisy in their 10 operation. It is in order to confine the noise that the sound-deadening casing which forms the subject of this invention has been provided.

The casing is shown in its preferred form 15 in Figures 1, 2 and 3, and comprises a lower member 15 and a hood or cover 16 pivotally mounted on a hinge 17 fast to the lower member. Said lower member is provided with an opening 18 at the front 20 through which the keyboard-extension of the machine protrudes to render the same operable. The borders around said opening are effectively sealed against the emission of sound, and both the lower member and 25 the cover are lined with layers of sound-deadening material to further refract the sound waves and confine them within the casing. Said layers of sound-deadening material may be substituted by a double 30 metal wall, or the casing and cover may be built with a single wall, as shown in the drawings, depending on the degree of noise eliminating efficiency which may be required.

In order that the line-space lever 13 may 35 be manipulated without displacing the cover, there is provided an opening 19 between the cover and the casing adjacent the path of said lever 13 and in front thereof, so that a finger 20 may reach the lever 13 to return the carriage 11 and to line-space a work-sheet around the platen 12. Said opening 40 19 is provided with a closure for further preventing the emission of sound while the machine is operated. The closure consists, 45 in its preferred form, of a double door arrangement and linkage designed to simultaneously operate both doors when a finger-piece 21 is rotated.

In order that the lever 13 may be reached 50 with the finger 20 to return the carriage, there is provided mechanism whereby the opening 19, normally closed to prevent the emission of sound, may be opened. To this end the double door arrangement, which is 55 shown in its effective position in Figure 2, comprises metal plates 22 and 23 rockably mounted on hinge-shafts 25 and 26. Said metal plates are swung open by means of the finger-pieces 21 fast to the shaft 26 against 60 the tension of springs 24 wound around the pivot shafts. The open position of the doors is shown in Figure 3. There is provided linkage operatively connecting the two doors for synchronizing their movement so 65 that both doors will operate simultaneously.

Said linkage comprises links 27 connected to the plates 22 and 23 at 28, and co-operating with vertically disposed arms 29 to which the links 27 are connected at 32. Said arms are fulcrumed at 30 and connected together by means of a pin-and-slot arrangement 31, the rearward travel of the arms being limited by pins 33 fast to the cover 16. The bearing in which the hinge-shaft 26 rocks is formed by plates 34 fast to the 70 lower member 15 by means of screws 35. Similarly numbered plates serve as bearings for the shaft 25 and are fastened to the cover 16 by means of similarly numbered screws 35. The doors for closing the opening 19 consist of the sheet-metal plates 22 and 23, the inner side of which is lined with felt 37 to render the same sound-proof. Around the borders of said plates there are provided felt strips 36 to more effectively 75 prevent the leakage of sound waves, said strips being fastened into recesses in the cover in the lower member.

In some cases it may be desired to open the doors by pushing the doors in with the finger, while in other cases it may be desired to use the finger-pieces 21, of which there is one at each end of the shaft 26, so that either hand may be used to operate the finger-pieces. This is advantageous due to 90 the disposition of the carriage in the Underwood machine, in which the line-space lever 13 is usually operated with the left hand while the carriage-release lever 14 is generally manipulated with the right hand. It will 100 be noted that when the cover is opened to insert a fresh sheet around the platen, the upper door 22, which is rockably mounted on the cover, and the linkage therefor, will be separated from its co-operating door 23 105 and its linkage which is mounted on the casing. To render separable the two sets of links, the arrangement 31 has the slot opened to allow the pin to slide out, as 110 shown in dot-and-dash lines in Figure 2.

Figures 5 and 4 illustrate, respectively, the front view and the cross-sectional view in elevation of a modification of the mechanism for synchronizing the movement of the two doors, and the linkage provided in the 115 preferred form is substituted by two geared sectors 38 pivotally mounted on shafts 39 which carry the doors 40 fast thereon. Said shafts are rockably mounted on bearings 41 respectively fastened to the cover 42 and to 120 the casing 43 by means of screws 44. The sectors 38 are fastened to the shafts 39 by means of a hub-and-pin arrangement 45, and the upper sector is provided with a bent tab 46 forming a finger-piece through which 125 the doors are opened. The doors are covered with sound-deadening material 48, and are returned to their effective or closed positions by means of springs 47 when the pressure on the tab 46 is released. It will be noted 130

that in this modification one door is hung on the cover while the other is mounted on the casing, and that the opening through which the finger-pieces may be reached is formed 5 between the cover and the casing, so that when the cover is swung backwardly the upper door and its corresponding sector 38 moves with the cover.

Other variations of means for closing the 10 opening through which the finger may reach the carriage-control levers are shown in Figures 6, 7, 8 and 9. Figures 6, 7 and 8 illustrate a variation in which the opening is in the cover, while Figure 9 shows a construction in which the joint between the cover 15 and the casing forms the opening.

Referring more particularly to Figure 6, a casing 49 is shown, upon which a cover 50 is rockably mounted on a hinge 51. In said 20 cover 50 there is provided an opening 52 extending substantially the full width of the cover and in front of the levers 13 and 14. Said opening is provided with a closure consisting of celluloid strips 53 having the inner sides covered with sound-deadening material 54. The celluloid strips are fastened to the cover by means of screws 55 through 25 metal strips 56. Normally the two celluloid strips are abutting against each other, as shown in full lines in said Figure 6, the abutment being formed by bent edges 57 along the full length of the strips. When it is desired to reach the lever 13, a finger 58 may be thrust through the opening by forcing 30 open the celluloid strips, as shown in dot-and-dash lines in Figure 6. The carriage is then returned to its starting position by sliding the finger along the opening and at the end the finger is withdrawn, thereby allowing the spring of the celluloid strips to act and to effectively close the opening. The cover 50 is shown partially opened 35 in dot-and-dash lines to illustrate that the opening and the closing means therefor form an integral part of said cover.

In Figures 7 and 8 another manner of closing an opening 59 in a cover 60 is shown. The cover is rockably mounted on a hinge 61 fast to a casing 62, and is shown in its 40 open or displaced position in dot-and-dash lines. In this form of the invention only one door is provided, and it comprises a sheet-metal strip 63 fast to a pivot shaft 64 manually operable by means of finger-pieces 65 which extend to the exterior of the cover. The shaft 64 is hinged in plates 66 which are fast to the cover by means of screws 67, and the same plates 66 are also used to 45 secure a strip of felt 68 around the borders to effectively seal the joint between the cover 60 and the edges of said metal strip 63. The latter is covered with a felt lining 69. The door may be swung open to a position 50 shown in dot-and-dash lines in Figure 8 in two different manners, by pushing a finger

76 against the pressure of a spring 70, which tends to hold the door closed, or by means of the finger-pieces 65 on the shaft 64.

In Figure 9 there is shown a modification of the closure illustrated in Figure 6. One 70 of the features of this form is that the slot or opening for operating the control levers is formed between the casing and the cover. Another feature is that the closure consists of sound-deadening front strips 71 backed 75 by rubber strips 72, the two strips being stuck together and fastened, respectively, to the cover and to the casing by means of a metal strip 73 and screws 74. This closure permits a local yield when the finger is 80 thrust through the opening to reach the carriage-control levers. The strips 71 are composed preferably of plush to present a smooth surface to the fingers as they slide lengthwise of the slot. 85

Closure-plates 80 are provided to close the openings between the slot-closing devices 53 (Figure 6) and 71 (Figure 9) at their ends to prevent escape of sound from 90 said openings. In Figure 9 each closure-plate 80 is split at 81, so that the upper part may swing back with the cover, the other part being secured to the body-part of the casing. 95

From the foregoing it will be understood that there is provided a sound-deadening casing which completely encloses the typewriter machine, including the finger-pieces on the carriage, such as the line-space handle 13, the carriage-return handle and the carriage-release handle (not shown). Said casing has a slot at the front through which the fingers of the operative may reach to 100 said enclosed finger-pieces on the typewriter carriage. The slot is normally closed by suitable slot-sealing devices to prevent the escape of sound from the casing through 105 said slot. The slot-sealing devices are arranged to be pushed aside conveniently by the finger of the typist as it moves toward the finger-piece on the carriage. It will further be understood that there is provided a window in the cabinet which not only 110 renders the typing visible, but also enables the operative to observe the position of the carriage and especially the finger-pieces thereon with reference to the slot in the cabinet, so that the finger may be inserted in the proper position lengthwise of the slot 115 according to the position of the desired finger-piece on the carriage. 120

In Figures 1 to 5 and in Figure 9 the slot in the cabinet is formed between the cover and the front wall of the body-part of the casing, and consequently there are provided two slot-sealing devices which co-operate 125 with each other to close said slot, one of said slot-sealing devices being supported on the body-part of the cabinet, and the other being carried by the cover of the cabinet, so 130

that it may be carried with the cover when the latter is opened to give access to the platen.

In Figures 1 to 5, inclusive, and Figures 5 7 and 8, the slot-sealing elements are pivoted and are composed of metal. These devices may be pushed inwardly by the finger of the typist as it reaches to the finger-piece on the carriage, or the devices may be operated by 10 individual finger-pieces by one hand while the other hand reaches up through the slot to the finger-piece on the carriage.

In Figures 7 and 8 the finger-slot is provided in the cover. In this form of the invention only a single slot-sealing element is used which is carried by the cover. In Figure 6 the slot is also provided in the cover, but two oppositely-disposed slot-sealing devices are used.

20 In Figures 2 and 4 there are provided two slot-sealing devices, one on the cover and the other on the body-part of the cabinet, said devices being connected to each other, so that they may be operated simultaneously, and also to enable the connection to be broken when the cover is swung back to give access to the platen.

It will also be noted that in Figure 9 30 one of the slot-sealing devices is carried by the cover, while the other one is carried by the body-part of the cabinet.

In order to render visible the work-sheet around the platen when the typewriter is operated in the casing, there is provided an 35 opening in the cover which is sealed against the emission of sound by means of a plate of transparent material. Said plate is indicated throughout the several views and modifications by the numeral 75.

40 Variations may be resorted to within the scope of the invention, and portions of the improvements may be used without others.

Having thus described my invention, I claim:

45 1. The combination with a typewriting machine including a keyboard, a carriage and control levers on said carriage, of a sound-deadening casing including a lower member having a keyboard opening and a liftable hood mounted on said lower member, said casing otherwise enclosing the machine and including said carriage levers, said casing having a finger-slot, said carriage levers being accessible to the hand of the operator thrust through said slot for manipulation, without lifting the hood of said casing; said finger-slot extending along the casing to accommodate the carriage-driving movements of the hand.

60 2. The combination with a typewriting machine including a keyboard, a carriage and control levers on said carriage, of a sound-deadening casing including a lower member having a keyboard opening and a hood mounted on said lower member, said

casing otherwise enclosing the entire machine and including said carriage levers, said casing having a finger-slot, said carriage levers being accessible to the hand of the operator thrust through said slot, said slot extending along the casing to accommodate the carriage-driving movements of the hand, and an openable but normally closed slot-sealing device for preventing the emission of sound through said slot. 75

3. The combination with a typewriting machine including a keyboard, a carriage and carriage-control finger-pieces, of a sound-deadening casing open for the keyboard, said casing otherwise enclosing the machine and having a normally closed slot at the front thereof through which the hand of the operator may be thrust to manipulate said finger-pieces. 80

4. The combination with a typewriting machine including a keyboard, a carriage and carriage-control finger-pieces, of a sound-deadening casing including a lower member having an opening at the front through which the keyboard protrudes and a liftable hood mounted on said lower member, said casing otherwise enclosing the machine and having a normally closed slot at the front thereof through which the hand of the operator may be thrust to manipulate 90 said finger-pieces, said slot being partly in the front wall of the casing and partly in the front wall of the hood, and openable but normally closed slot-sealing devices for preventing the emission of sound through 95 said slot. 100

5. The combination with a typewriting machine including a keyboard-extension, a carriage and controlling levers therefor, of a sound-deadening casing open for the keyboard-extension, said casing having a finger-slot through which the controlling levers may be reached, and means for preventing the emission of sound through said finger-slot, said means including a double-door arrangement, linkage to synchronize the movement of the two doors, finger-pieces for opening said doors and springs for normally holding said doors in their closed positions. 110

6. The combination with a typewriting machine including a keyboard-extension, a carriage and controlling levers therefor, of a sound-deadening casing and a cover therefor, the casing being open for the keyboard-extension, said casing having a finger-slot extending along the casing for operating the controlling levers, and means for preventing the emission of sound through said finger-slot, said means including two pivotally-mounted metal doors, springs to keep the doors normally closed, linkage partly fastened to the cover and partly to the casing to synchronize the movement of the two doors, a lining of sound-deadening 120 125 130

- material fast to the inner side of said doors and finger-pieces for opening said doors.
7. The combination with a typewriting machine including a keyboard-extension, a carriage and controlling levers therefor, of a sound-deadening casing open for the keyboard-extension, said casing having a finger-slot in front thereof through which the controlling levers may be reached to manipulate the carriage, and means for preventing the emission of sound through said slot, said means including two pivotally-mounted metal doors, a felt lining fast to the inner side of said doors, springs to hold the doors closed, two geared sectors fast to the pivot upon which the doors are mounted cooperating to synchronize the movement thereof and a finger-piece for opening the doors.
- 10 8. The combination with a typewriting machine including a keyboard-extension, a carriage and controlling levers therefor, of a sound-deadening casing open for the keyboard-extension, said casing having a finger-slot in front thereof to accommodate the carriage-driving movement of the hand, and means for rendering sound-proof said finger-slot, said means including two celluloid strips abutting against each other, fast to the borders of said finger-slot and forming a bell-mouth or funnel entrance for the finger to reach and operate said controlling levers.
- 15 9. The combination with a typewriting machine including a keyboard-extension, a carriage and controlling levers therefor, of a sound-deadening casing open for the keyboard-extension, said casing having a finger-slot for operating said controlling levers, and means for preventing the emission of sound through said finger-slot, said means including a pivotally-mounted door having a felt lining and a felt strip around the borders of said finger-slot, a spring to normally hold the door closed and a finger-piece to open said door against the pressure of said spring.
- 20 10. The combination with a typewriting machine including a keyboard-extension, a carriage and controlling levers therefor, of a sound-deadening casing open for the keyboard-extension, and having a finger-slot in front of the controlling levers and adjacent thereto, and means for preventing the emission of sound through said slot, said means comprising two flap-closures abutting against each other and having the outer edges fast to the borders of the slot, said closures consisting of a felt outer layer and a rubber inner layer providing a local yield as the finger is slid along the slot to operate the carriage-controlling levers.
- 25 11. The combination with a typewriting machine including a keyboard, a carriage and control levers on said carriage, of a sound-deadening casing including a lower member having a keyboard opening and a hood mounted on said lower member, said casing otherwise enclosing the entire machine and including said carriage levers, said casing having a finger-slot, said carriage levers being accessible to the hand of the operator thrust through said slot, said slot extending along the casing to accommodate the carriage-driving movements of the hand, and an openable but normally closed slot-sealing device for preventing the emission of sound through said slot, said sealing device being mounted to be pushed aside by the movement of the hand rearwardly through said slot to reach said carriage levers.
- 30 12. The combination with a typewriting machine including a carriage and carriage-control levers therefor, of a sound-deadening casing having a finger-slot at the front therein through which the fingers may reach to the enclosed carriage-control levers on the carriage and slot-sealing devices to prevent the emission of sound thereof, said slot-sealing devices being arranged to be opened as the fingers of the hand are thrust through the finger-slot toward the carriage-control levers.
- 35 13. The combination with a typewriting machine including a carriage and finger-pieces for controlling said carriage, of a sound-deadening casing including a lower member and a liftable hood mounted on said lower member, said hood having a finger-slot at the front therein through which the fingers of the hand may reach to the enclosed finger-pieces on the carriage, and sealing elements for said slot.
- 40 14. The combination with a typewriting machine including a carriage and controlling levers therefor, of a sound-deadening casing including a lower member and a cover therefor, said casing having a finger-slot, formed between said lower member and said cover, and slot-sealing devices carried partly by the cover and partly by the lower member.
- 45 15. The combination with a typewriting machine, including a carriage and controlling levers therefor, of a sound-deadening casing having a finger-slot at the front through which the fingers of the operative may be thrust to operate said carriage, and slot-sealing devices oppositely disposed and of flexible material to yield when the fingers are thrust through the slot to operate the levers on the carriage.
- 50 16. The combination with a typewriting machine including a carriage and controlling levers therefor, of a sound-deadening casing having a finger-slot at the front through which the fingers of the operative may be thrust to manipulate the carriage, and slot-sealing devices oppositely disposed

- and of flexible material to yield when the fingers are thrust through the slot, said slot-sealing devices being made of celluloid or the like to present a smooth surface to the fingers during the movement of the carriage. 5 within the casing so that one may be operated simultaneously with the other.
17. The combination with a typewriting machine including a carriage and controlling levers therefor, of a sound-deadening casing having a finger-slot at the front 10 through which the fingers may be thrust, and slot-sealing devices oppositely disposed and of flexible material to yield when the fingers are thrust through the slot to operate the levers on the carriage, said slot-sealing devices being composed of celluloid strips having felt strips fastened thereto to reflex the sound waves and to prevent their exit through the slot. 15
18. The combination with a typewriting machine including a carriage and controlling levers therefor, of a sound deadening casing having a lower member, a cover therefor, and a finger-slot in said cover, and slot-sealing devices oppositely disposed to yield 20 when a finger is thrust through the slot to operate said controlling levers.
19. The combination with a typewriting machine including a carriage and controlling levers therefor, of a sound-deadening casing having a cover and a finger-slot in 25 said cover, and slot-sealing devices composed of felt-covered rubber strips stuck together and oppositely disposed to yield when a finger is thrust through the slot to operate said controlling levers. 30
20. The combination with a typewriting machine including a carriage and finger-pieces therefor, of a sound-deadening casing having a finger-slot adjacent said finger-pieces and in front therof, and slot-sealing devices pivotally mounted and arranged to be pushed inwardly by the fingers of the same hand which reaches to the finger-pieces of the carriage. 40
21. The combination with a typewriting machine including a carriage and finger-pieces therefor, of a sound-deadening casing having a slot adjacent said finger-pieces, slot-sealing devices fast to a pivotally 45 mounted rock-shaft, said devices being arranged to be pushed inwardly by the fingers of the same hand which reaches to the finger-pieces on the carriage, and finger-pieces fast to the ends of the rock-shaft for 50 opening the slot-sealing devices. 55
22. The combination with a typewriting machine including a carriage and finger-pieces therefor, of a sound-deadening casing having a slot adjacent said finger-pieces, 60 and slot-sealing devices pivotally mounted and arranged to be pushed inwardly by the fingers of the same hand which reaches to the finger-pieces of the carriage, said slot-sealing devices being operatively-connected 65
23. In a sound-proof cabinet for a typewriting machine having a carriage and finger-pieces on said carriage, said cabinet having a slot through which the fingers of the operative may reach to the finger-pieces on the carriage, means to normally keep said slot closed, and a window in said cabinet through which the position of the carriage may be observed, so that the operative may know where to thrust the fingers into the slot lengthwise thereof to the finger-pieces 70 on the carriage. 75
24. In a sound-proof cabinet for a typewriting machine including a carriage and finger-pieces on said carriage, said cabinet having a slot through which the fingers of the operative may reach to the desired finger-piece on the carriage, means to normally keep said slot closed, and a finger-piece to actuate the slot-closing means. 80
25. In a sound-proof cabinet including a body part and a cover to completely enclose a typewriting machine including a carriage and finger-pieces on said carriage, said cabinet having a slot through which the fingers of the operative may reach to the desired finger-piece on the carriage, means to normally keep said slot closed, and a finger-piece to actuate the slot-closing means. 90
26. In a sound-proof cabinet for a typewriting machine including a carriage and finger-pieces on said carriage, said cabinet including a body-part and a cover, the cabinet having a finger-slot formed between the body-part and the cover, slot-closing means including two elements, one supported on the cover, the other supported on the body-part, and means to actuate said elements 100 simultaneously to open said slot. 105
27. In a sound-proof cabinet for a typewriting machine including a carriage and finger-pieces on said carriage, said cabinet including a body-part and a cover, the cabinet having a finger-slot formed between the body-part and the cover, slot-closing means extending along said slot, said slot-closing means including two elements, one supported on the cover, the other supported on the body-part, a finger-piece connected to one of said elements to actuate it, and a connection between said elements to cause them to be actuated simultaneously by the last-named finger-piece to open said slot so that the fingers of the typist may reach into said cabinet to the finger-pieces on the carriage. 110 115
28. In a sound-proof cabinet for a typewriting machine including a carriage and finger-pieces on said carriage, said cabinet including a body-part and a cover, the cabinet having a slot formed between the body-part and the cover, slot-closing means extending along said slot, said slot-closing 120 125

means including two elements, one supported on the cover, the other supported on the body-part, and means including a connection between said elements to operate them simultaneously to open said slot, so that the fingers of the typist may reach into the cabinet to the finger-pieces on the carriage, said connection enabling one of said elements to be separated from the other while

10 the cover is being opened.

29. In a sound-proof cabinet for a type-writing machine including a carriage and finger-pieces on said carriage, said cabinet having a slot through which the fingers of

15 the operative may reach to the desired finger-piece on the carriage, and means to normally keep said slot closed, said means including a slot-closing device extending along said slot, said device including a strip of

20 plush and an elastic backing for said plush.

30. In a sound-proof cabinet for a type-writing machine including a carriage and finger-pieces on said carriage, said cabinet having a slot through which the fingers of

the operative may reach to the finger-pieces on the carriage, means to normally keep said slot closed, said cabinet including a cover and a body-part, and having a slot formed between said body-part and said cover, and slot-closing means including two elements co-operating with each other and extending along said slot, one of said elements being carried by the cover, the other being carried by the body-part, each element including a strip of plush and an elastic backing for said plush.

31. In a sound-proof cabinet for a type-writing machine including a carriage and finger-pieces on said carriage, said cabinet having a slot through which the fingers of

15 the operative may reach to the finger-pieces on the carriage, two slot-closing strips extending along said slot in V-shaped cross-sectional relation, and closure-plates to co-operate with the ends of said strips to prevent the escape of sound from said cabinet.

JOHN WALDHEIM.
